COOKING STOVE

Sheldon M. Rutter, Lake Forest, Ill., assignor to Crown
Stove Works, Chicago, Ill., a corporation of Illinois

Application December 13, 1955, Serial No. 39,325

Term of patent 3½ years

(Cl. D81—4)

Fig. 1.

Fig. 2.

Figure 1 is a perspective view of a cooking stove embodying my new design.

Figure 2 is a side elevational view of the same.

The characteristic feature of my design for the cooking stove disclosed resides in the backguard panel having the configuration shown.

I claim:

The ornamental design for a cooking stove, substantially as shown and described.
